*O. & D. Parker,
Clapboard Machine.
Patented Dec. 24, 1834.*

Dec. 24, 1834 8561X

Otis Parker and Daniel Parker of Hubbardston in the County of Worcester and Commonwealth of Massachusetts.

Letters Patent.

The Schedule referred to in these Letters Patent and making part of the same, containing a description in the words of the said Otis Parker & Daniel Parker, themselves of their improvement in the method of sawing clapboards by means of a machine called "a Clapboard Machine".

To all to whom these presents shall come.

Be it known, that we, Otis Parker & Daniel Parker, both of Hubbardston in the County of Worcester and Commonwealth of Massachusetts, Millers, have invented, made, constructed & applied to use a new and valuable improvement in the method of sawing clapboards, by means of a machine called a Clapboard Machine - specified and described in the words following, to wit,

The machine now in use for sawing clapboards being mostly designed for parts of the country where timber is very abundant, are constructed in such a way as to cause a prodigious waste of timber. The machines too, are built at an inconvenient expense. Our machine it is believed, is free from both of these difficulties, and saves another evil which is the subject of much complaint, to wit, the edge of the clapboard. Our machine performs the work in such a way as to leave the edge of the Clapboard of the proper thickness.

The frame upon which the machine rests is made of firm wood and is in the form of a parallelogram. Parallel to the sides of the frame and at nearly an equal distance from them, being between them, are two beams firmly connected to the said pieces at each end of the frame. The

Drawing

The carriage bearing the timber to be sawed, rests on one of these beams, and upon the side of the frame. Upon the carriage are two circular head-blocks, upon which the timber to be sawed rests. Through the tops of these head-blocks passes a roller, having firmly attached to one end of it, a ratch-wheel, valve & branch. Near each end of this roller is a rope. One end of each of these ropes is fastened to the roller, so that when the roller is turned by the crank, the ropes are wound round it. The other ends of the ropes are fastened to the ends of a piece of wood, each end of which rests upon the head-blocks. This piece of wood or bar, is accommodated with a dog at each end to hold the stick or timber to be sawed. The timber is placed upon the head-blocks and the under-side of this bar, and by turning the roller the timber is drawn upwards, when it is drawn up to the proper place, it is there held by means of the ratch-wheel which is also accommodated with a dog or catch. This catch is lifted out of the ratch-wheel as often as the carriage goes back, and the weight of the timber brings it down through a space equal to the thickness of the back of the clapboard, and this space is regulated by the distance between the teeth of the ratch-wheel.

We use the circular saws upon the same shaft with the saw is a pulley, for a band to connect the machine with the moving power. There is another shaft, having also a pulley, and band to connect it with the other pulley upon this last shaft is the necessary gear to move the carriage.

Explanation of the drawing - A. A. the frame of the machine. b. saw. c. pulley upon the same shaft with the saw. d. circular blocks. e. e. carriage bearing the head-blocks. f. roller. g. ropes. h. over end attached to the roller. i. ratch-wheel. k. crank. l. l. dog to confine the timber to be sawed. m. the bar to which the timber is attached. n. wood upon which the timber is placed. o. a

of the catch or dog for the hatch-wheel g . h , a pin for raising the catch z . t . s or for throwing the carriage out of gear, v , a part of the lever, b . pulley, t . pinion for moving the carriage.

Operation of the machine.—The stuff for clapboards is prepared in a common saw-mill, by quartering the logs, and cutting the required length. The sharp edges of these quarters are then cut off so as to leave them of the desired width of the clapboards. They are then spilted or fived for placing them upon the head-blocks. When a stick, prepared in this way, is placed under the bar W . and fastened by the dogs e . e , the carriage is put in motion, and when the carriage has passed by the saw, the pinion o . is thrown out of the notch attached to the bottom of the carriage, and by means of a weight, the carriage is drawn back to its original position; and as it passes back the catch or dog is raised out of the notch-wheel g ; and the wheel g , in the roller v , is turned by means of the weight of the timber attached to the bar W , and the timber slides down upon the circular head-blocks, a space equal to the thickness of the back or thick edge of the clapboard. When it has fallen through this space, it is stopped by the catch or dog of the wheel g , when the carriage was drawn back by the weight, the pinion o . was thrown into gear by the lever b , and the carriage again moves forward, and this operation is repeated until the timber or plank is wholly sawed. All this claim as invention, is the manner of presenting the stuff or timber to the saw by means of circular head-blocks, as is above described.

See witness whereof we have hereunto set our hands this twenty-fifth day of October in the year of

Lord one thousand eight hundred & thirty four.
